UNITED STATES PATENT OFFICE.

CARL SCHOLL, OF GÖPPINGEN, GERMANY.

MAGNETIC SEPARATOR.

SPECIFICATION forming part of Letters Patent No. 715,160, dated December 2, 1902.
Application filed September 13, 1901. Serial No. 75,342. (No model.)

To all whom it may concern:

Be it known that I, CARL SCHOLL, a citizen of the German Empire, residing at Göppingen, in the Kingdom of Württemberg, Germany, have invented certain new and useful Improvements in Magnetic Separators; and I do hereby declare the following to be a full, clear, and exact description of the invention, such as will enable others skilled in the art to which

it appertains to make and use the same.

The present invention relates to electromagnetic separators or devices for separating metallic or magnetic particles, pieces, or constituents from a mass containing them, together with non-magnetic portions or constituents.

The object of my invention is to effectually eliminate the necessity of frequent interruptions of the operation of the separator or of applying scraping devices to apparatus of this kind.

To this end my invention involves the use of means in connection with a separating-drum having a number of electromagnets arranged within its periphery whereby no current will pass through the coils of the rotating electromagnets at certain positions in the course of their rotation, whereby whenever these electromagnets and the drum in which they are arranged reach such point in their way the separating-drum will cease to attract the metallic or magnetic particles or pieces withdrawn from the mass, and these particles or pieces will drop away from the drum to be carried to the collecting-point in a manner readily understood and well known.

Other features of the invention will be brought out in the following description and pointed out in the claims annexed.

In the accompanying drawings, Figure 1 represents a side elevation of a separating-machine embodying my invention and employing three separating-drums; Fig. 2, a front elevation of the same; Fig. 3, a vertical transverse section through one of the drums, on an enlarged scale; and Fig. 4, a similar section on the line A A, Fig. 2, to show how the electric current is supplied. Fig. 5 is an enlarged detail view showing the method of mounting the electromagnets. Fig. 6 is a diagrammatic view illustrating the connections

between the sections of the distributor and the several sets of magnets.

As shown in the drawings, a number of separating-drums *b* are mounted in the machine-frame *a*, the shafts or journals *c* of said drums being provided with cog-wheels *d*, engaging with intermediate cogs *e*, one of said intermediate cogs *e* being driven from a belt-pulley *f* in a manner well known and understood.

The journal *c* of the upper drum *b* extends beyond the frame *a* at the opposite side and is there provided with a sprocket-wheel *g*, over which passes a chain *m*, which in turn engages with the sprocket-wheels *i*, keyed to the spindles or shafts of a series of rotary brushes *h*, which brushes are arranged in contact with the drums *b*, as shown. By this means when the drums are rotated the rotary brushes are caused to rotate in contact with them in an opposite direction and to keep the said drums clean; but these brushes are by no means adapted or strong enough to scrape off from the drums any metallic or magnetic particles or pieces adhering to them by virtue of the magnetic attraction of the drums. In order to adjust the tension of the chain *m*, an idler-sprocket *l* is journaled in an adjustable bearing-bracket *k*, which may be moved away from or toward the chain, as desired and as will be understood.

The number of separating-drums to be employed depends on the character of the work to be performed. The arrangements and construction of actuating devices for the drums and the cleaning-brushes thus far described have been set forth in illustrating a device to which my invention may be applied. The particular features of the said invention will now be given in detail.

As seen from Figs. 3 and 6, the separating-drum is equipped with electromagnetic coils arranged in series, six sets of such coils being employed in the machine illustrated. The coils may be arranged in any desired manner, but preferably are constructed as follows: The separating-drum is provided inside with a series of longitudinally-arranged bars *o o'*, of soft iron. On the bars *o* (which alternate with the bars *o'*) are mounted a series of electromagnets *n*, the cores *n'* of which are secured to the respective bar *o* in any suitable

way, as by screwing them into said bar. The coils *n* are arranged in pairs, a number of said pairs being arranged on each bar *o* to form a set, one half of the magnets of a set 5 pointing in one direction and the other half in the other direction. The bars *o* serve to improve the magnetic circuit, the connection of the coils *n* being such as to put them in series with each other, as shown in Fig. 6, all 10 the positive poles of the magnets on one side of the bars *o* facing in one direction and all the positive poles of the magnets on the opposite side of the bars facing in the opposite direction, the two magnets of each pair being 15 wound in a reverse direction and the coils of a set being in series.

On the shaft *c* of each separating-drum *b* and between the cog *d* and said drum is fastened a distributor *p*, which rotates with its 20 drum, and the particular arrangement of which, in conjunction with its current-supplying brushes, constitutes the most important part of my present invention. This current-distributor *p* comprises as many sections 25 1^a to 6^a as there are sets of electromagnetic coils *n*—in the present example six—said sections being separated by insulating-strips *t*, as shown.

The current-supplying brushes *q*, *r*, and *s* 30 are mounted on the machine-frame in any desired or convenient manner; but they are always connected with the sources of current in such a way that the two outer ones convey a current of the same polarity, while the intermediate one carries a current of opposite polarity. In the example given in the drawings the outer brushes *q*, *r* carry a + current, while the middle brush *s* conveys a — current. The distributor-sections 1^a to 6^a are connected 35 in the following manner to the sets of coils 1 to 6 by means of the conductors *w*¹ to *w*⁶, each consisting of two insulated wires, as indicated in Figs. 3 and 4. As seen from those 40 figures, one of the two wires *w*¹ from the distributor-section 1^a is connected to the positive terminal of the coil 1 and the other to the negative terminal of the coil 6. One of the two wires *w*² from the section 2^a is connected to the positive terminal of the coil 2 45 and the other to the negative terminal of the coil 1, and so on, the two wires from each section being connected in succession to the positive and negative terminals, respectively, of the corresponding coils of the series of electromagnets *n*. Under the construction thus 50 described the current from the brushes *q* and *r* will pass through the distributor-sections with which these brushes are in contact and thence through the coils *n* on opposite sides 55 of the drum out through the brush *s*, but will not pass through the distributor-section lying between the brushes *q* and *r*, so that the coils at that part of the separator-drum which is 60 connected with said section will receive no current, and hence will not be magnetic. This periodic stoppage of magnetism takes 65 place in turn for each section of the drum and

always when the same comes to a predetermined location, which location may be suitably selected in such a way that the separated magnetic material as it is released from the said drum will drop or can be blown into suitable conveyers or chutes, as will be readily understood. 70

The advantage arising from my invention 75 is that under the same no scraping devices or intermittent interruptions of the operation of the separator become necessary. The rotary brushes *h* are merely provided to keep the periphery of the drum clean and not for 80 the purpose of scraping magnetic material from the same.

It will be seen from the above that under my invention the separating-drum has on its surface only a partial magnetic field, which 85 field, moreover, rotates relatively in a direction opposite to the rotation of the drum and preferably at the same speed as that of the said rotation of the drum, so that the non-magnetic portion of the drum will virtually 90 be stationary with reference to the fixed frame of the separator. It will be noted, moreover, that I effect this result by arranging the two brushes carrying current of one polarity so that they will never touch adjoining sections 95 of the distributor-ring and by placing the brush carrying current of opposite polarity at an intermediate point on the distributor.

What I claim, and desire to secure by Letters Patent of the United States, is—

1. In a magnetic separator a rotary separating-drum in combination with a series of electromagnets for producing a partial magnetic field on the surface of the drum; a rotary sectional current-distributor ring; two brushes for supplying current of one polarity and so arranged as never to impinge against adjoining distributor-sections, a third brush impinging against an intermediate section and arranged to supply current of opposite polarity, and connections between the coils of the electromagnets and the sections of the current-distributor, whereby current is fed only to a portion of the coils and a portion of the surface of the separating-drum is thus 115 constantly non-magnetic.

2. In a magnetic separator, a rotary drum provided with a plurality of sets of interiorly-disposed electromagnets, a rotary distributor-ring divided into as many sections as there 120 are sets of magnets, three brushes for supplying current to different sections of the distributor, two being of one polarity and one of the opposite polarity, and connections between the coils of the magnets and the sections of the distributor, whereby current is 125 fed to the magnets connected to the sections of the distributor intermediate the brushes of opposite polarity and not to those connected to the sections intermediate the brushes of the same polarity.

3. In a magnetic separator a rotary drum, a plurality of sets of electromagnets disposed therein, a distributor-ring rotating with the

drum and consisting of insulated sections corresponding in number to the sets of magnets, connections between the several sections of the ring and the respective sets of magnets, two brushes carrying a current of the same polarity and one brush carrying a current of the opposite polarity all contacting with the distributor-ring at spaced intervals, whereby current is fed to the magnets connected with the sections intermediate the brushes of opposite polarity and not to the magnets connected with the sections intermediate the brushes of the same polarity, resulting in a shifting partial magnetic field upon the surface of the drum.

4. In a magnetic separator, a rotary drum, a plurality of sets of electromagnets disposed therein and each set coextensive with the length of the drum, a rotary distributor-ring revolving with the drum and composed of sections corresponding in number to the sets of magnets, connections between the sections

of the ring and the two adjacent sets of magnets, three brushes contacting with the distributor-ring, two of the brushes carrying a current of the same polarity and disposed in such manner that there shall at all times be a complete section thereof interposed between the same, and the other brush carrying a current of opposite polarity, whereby current is fed to the magnets connected with the sections intermediate the brushes of opposite polarity and not to the magnets connected with the section intermediate the brushes of the same polarity, thus resulting in a shifting partial magnetic field upon and rotating in an opposite direction relative to the drum.

In testimony whereof I affix my signature in presence of two witnesses.

CARL SCHOLL.
